Primary Examiner — John Windmuller*Assistant Examiner* — Steven Czyz(74) *Attorney, Agent, or Firm* — Rossi, Kimms & McDowell LLP(57) **CLAIM**

The ornamental design for an umbrella handle, as shown as shown and described.

DESCRIPTION

FIG. 1 is a perspective view of an umbrella handle showing a new design.

FIG. 2 is an alternate perspective view of the handle of FIG. 1.

FIG. 3 is a front elevation view of the handle of FIG. 1.

FIG. 4 is a rear elevation view of the handle of FIG. 1.

FIG. 5 is a side elevation view of the handle of FIG. 1, the opposite side elevation being a mirror image thereof.

FIG. 6 is a top plan view of the handle of FIG. 1; and,

FIG. 7 is a bottom plan view of the handle of FIG. 1.

The broken lines in the drawings depict portions of the article that form no part of the claimed design.

1 Claim, 3 Drawing Sheets---
